UNITED STATES PATENT OFFICE.

HENRY W. LOUDEN, JR., OF BEAUMONT, TEXAS.

DRILL.

Application filed April 18, 1922. Serial No. 554,465.

To all whom it may concern:

Be it known that I, HENRY W. LOUDEN, Jr., a citizen of the United States, residing at Beaumont, in the county of Jefferson and State of Texas, have invented new and useful Improvements in Drills, of which the following is a specification.

This invention relates to rotary drills, wherein use is made of two drills, the spindles of which are arranged one within the other and geared to a motor in a manner whereby the drills are rapidly rotated in opposite directions, the invention providing for simplicity in construction and compactness in the arrangement of the component parts.

In carrying out the invention, the drills are operated by means of an air motor which is equipped with an exhaust chamber designed to receive and store the water from the motor exhaust, and allowing the air to escape through the chamber.

Other objects and advantages will appear when the following detailed description is read in connection with the accompanying drawings, the invention residing in the construction, combination, and arrangement of parts as claimed.

In the drawings forming part of this application, like numerals of reference indicate similar parts in the several views and wherein:

Figure 1 is an enlarged fragmentary sectional view, showing the relative arrangement and mounting of the drill spindles.

Figure 2 is a transverse sectional view taken on line 2—2 of Figure 1.

Figure 3 is a similar view taken on line 3—3 of Figure 1.

Figure 4 is a longitudinal sectional view through the drill.

Figure 5 is a sectional view taken on line 5—5 of Figure 4.

Figure 6 is a sectional view taken on the line 6—6 of Figure 4.

Figure 7 is a detail view of one shaft and spindle.

Figure 8 is a detail view of one of the gears designed to mesh with said pinion.

Figure 9 is a view similar to Figure 8 showing the other gear which is adapted to surround the gear shown in Figure 8.

Referring to the drawings in detail, 10 indicates a jacket or tubular casing in which are arranged the drill spindles and the

mechanism for operating the drills, and this jacket may be of any suitable dimensions without departing from the spirit of the invention. In accordance with the present invention, use is made of two drills indicated 60 at 11 and 12 respectively, these drills being arranged one beneath the other and operate in the hole or opening in the ground at the same time. The drill 11 is supported by a spindle 13 which passes up into the jacket 65 10, while the drill 12 is supported by a spindle 14 which is arranged within the spindle 13 of the drill 11. The spindle 14 revolves within the spindle 13, while the latter mentioned spindle revolves in a tubular bearing 70 15. Threaded onto the lower end of the jacket 10 is a coupling 16, which is threadedly associated with the enlarged extremity 17 of the tubular bearing 15, and in this manner the bearing is connected with the 75 jacket 10. The spindle 14 is provided with a hole 18 to allow for the flow of water to the drill points. A pipe 18' is adapted for this purpose and is shown in full and dotted lines in Figure 4 of the drawing. The upper 80 end of the tubular bearing 15 is threaded into a cover or casing 19 which is utilized to house the gears to be presently described, and through the instrumentality of which the drills 11 and 12 are rotated in opposite 85 directions at a considerably high speed. The spindle 13 is secured to a cup-shaped gear 20, the teeth of which are arranged on the inside, while the spindle 14 which is arranged within the spindle 13 is keyed to a 90 smaller gear, the teeth of which are arranged on the outside, this gear being indicated at 21. Interposed between the gears 20 and 21 is a pinion 22 carried by a shaft 23 which is journaled in a bearing 24 forming part of the cover or casing 19. The jacket 10 which contains the construction just described, is fastened in any suitable manner to the drill stem 25 as at 26.

The shaft 23 is suitably connected to an 100 air motor indicated generally at 27, the operating fluid being connected from an air compressor (not shown) to the motor through the pipe 28. The pipe 28 passes through an exhaust chamber 29 which is 105 adapted to receive and store the water from the motor exhaust, an exhaust pipe 30 extending from the motor and terminating within the chamber 29 for this purpose. Surrounding the supply pipe 28 and enter- 110

ing the chamber 29 is a secondary exhaust pipe 31 which leads to the air compressor above referred to. The jacket which houses all of the mechanism is positioned within the well casing or the like indicated at 32.

In practice, the motor is started, incident to which the drills 11 and 12 are rapidly rotated in opposite directions, the operating fluid being conveyed to the motor through 10 the pipe 28, while the water from the exhaust of the motor is deposited in the chamber 29 by means of the pipe 30, while the exhaust pipe leads from the chamber to the air compressor as above stated. The drill is 15 not only very efficient in operation, but the construction and arrangement of the component parts are also very simple and compactly arranged.

While it is believed that from the foregoing description the nature and advantages of the invention will be readily apparent, I desire to have it understood that I do not limit myself to what is herein shown and described, and that such changes may be 25 sorted to when desired as fall within the scope of what is claimed.

What I claim is:

1. A drill of the character described comprising a jacket, a pair of superposed drills, 30 spindles supporting the drills and arranged

one within the other, a tubular bearing for the outermost spindle, said bearing being arranged within and connected to said jacket, a gear on each of said spindles, a pinion arranged between and meshing with said 35 gears, a motor for rotating said pinion whereby the drills and spindles are rapidly rotated in opposite directions.

2. A drill of the character described comprising a jacket, a pair of superposed drills 40 arranged beneath said jacket, spindles supporting said drills and arranged one within the other, a tubular bearing for the outermost spindle, said bearing being arranged within the jacket and having an enlarged extremity disposed beneath one end of the jacket, a coupling sleeve threadedly connected with said extremity and the adjacent end of said jacket, a gear on each spindle, a pinion arranged between and meshing with 45 said gears whereby the spindles and drills are rapidly rotated in opposite directions, a casing covering said gears and pinion and connected with the adjacent extremity of said bearing, and a motor arranged within 50 said jacket and operatively associated with said pinion for the purpose specified.

In testimony whereof I affix my signature.

HENRY W. LOUDEN, JR.
